CLAIM

The ornamental design for a wall hung toilet bowl, as shown
and described.

DESCRIPTION

FIG. 1 is a side elevational view of a wall hung toilet bowl
showing our new design;

FIG. 2 is a front elevational view;

FIG. 3 is a top plan view;

FIG. 4 is a bottom plan view;

FIG. 5 is a rear side elevation view; and,

FIG. 6 is a front, side, top perspective view.

The unshaded areas bounded by the broken lines in the
drawing views define the bounds of the claimed design and
form no part thereof.
